Fig. 2

Fig. 3

To all whom it may concern:

Be it known that I, Frederick G. Knowles, a citizen of the United States of America, residing in Rochester, in the county of Monroe and State of New York, have invented a new, original, and ornamental Design for Motion-Picture Projector, of which the following is a specification, reference being had to the accompanying drawings, forming a part thereof, in which:

Fig. 1 is a side elevation of a motion-picture projector showing my new design;

Fig. 2 is an end elevation of the motion-picture projector shown in the preceding figure; and

Fig. 3 is an end elevation taken from the opposite end of the motion-picture projector shown in the preceding figure.

The dominant features of my design reside in the portions shown in full lines.

I claim:

The ornamental design for a motion-picture projector, as shown and described.
